GOLF GAME PLATFORM OR SIMILAR ARTICLE

Michael D'Aliberti, Parsippany, N. J.

Application December 3, 1954, Serial No. 33,375

Term of patent 3½ years

(Cl. D34—5)

FIG. 1

FIG. 2

FIG. 4

FIG. 6

FIG. 5

Fig. 1 is a front perspective view of a golf game platform or similar article, showing my new design;

Fig. 2 is a rear perspective view thereof;

Fig. 3 is a side elevational view thereof;

Fig. 4 is an opposite side elevational view thereof;

Fig. 5 is a front elevational view thereof; and

Fig. 6 is a rear elevational view thereof.

I claim:

The ornamental design for a golf game platform or similar article, as shown.
